UNITED STATES PATENT OFFICE

2,326,178

SHEARS

Fred B. Seeberger, Yeadon, Pa.

Application September 28, 1942, Serial No. 459,907

5 Claims. (Cl. 30—245)

This invention relates to shears or scissors and particularly to a new and useful method for actuating the cutting members thereof.

The object of this invention is to provide a novel means whereby the power to operate such shears may be supplied by the palm and fingers of the hand instead of the usual fingers and thumb method of operating the cutting members.

Another object of this invention is to provide a simple palm and fingers controlled shears that may be readily used upon a plane surface such as a table, and in which shears, a single blade is actuated to perform the cutting operation.

Another object of this invention is to provide a shears having the articulated blade operating member lever and palm member positioned at a convenient angle with respect to the cutting blade, to facilitate control of the shears and prevent undue muscular fatigue commonly experienced in using the conventional type of shears.

Another object of this invention is to provide serrated edge blade members having non-radially generated teeth adapted to self lapping contact with each other to provide complementary cutting edges.

A further object of this invention is to provide a palm and fingers operated shearing means wherein the axis of the articulated blade supporting member, and its blade supporting base member is disposed in the longitudinal center of said members.

The improvement claimed is hereinafter fully set forth.

In the accompanying drawing,

Figure 1 is a perspective elevation of the invention.

Fig. 2 is an obverse perspective elevation of the invention, partly in section, and,

Fig. 3 is a fragmentary sectional view taken on line *a—a* in Fig. 2.

Reference numerals indicate the same parts in the several drawings.

In the practice of the invention as herein exemplified, it will be noted from the disclosure, that the natural position of the hand in gripping an object may be easily extended to the operation of the present invention with a minimum of fatigue. That extended use will not produce the usual occupational muscular cramp often experienced by those compelled to use the conventional tools provided for shearing. The principle of palm and fingers gripping of a shearing means may be applied without departure from the present invention to ordinary shears, scissors and metal snips, by substitution of suitable blades,

and the operative leverages proportioned to meet specific requirements.

Referring to Fig. 2, the articulated blade supporting member 1, which has a suitable blade 6 mounted thereon, is rigidly secured to a pivot member 2 by means of a set screw 3. The pivot member 2 is mounted in a blade supporting base member 4 which has a blade member 6 mounted thereon. These blade members may be attached to their respective supporting members by screws or other suitable means, the type shown in the drawing being known as pinking shear blades.

The base member 4 has an upright palm grip member 5 integral therewith and preferably disposed at approximately an angle of thirty degrees to permit easy natural position of the hand when operating the device upon a horizontal plane such as a table.

The articulated or movable blade member 1 extends a predetermined distance to the rear of the pivot member 2, said extension 7 being determined as to length by the leverage required to efficiently operate the cutting blades 6. The extended portion 7 is provided with a suitable configurated opening 7a adapted to operatively receive a complementary extension 8 on the finger lever 9, said lever 9 being pivotally mounted in the base member 4 and rigidly secured to the pivot member 10 by suitable means. The structure shown is a modification of a sector gear and for the purpose of simplicity is shown as a single tooth.

A suitable spring or resilient member 11, secured to the rear face of the finger lever 9, its outward free end 12 resting against the inner face of the palm grip member 5 provides means for retracting the finger lever 9 and the articulated blade supporting member 1 to operative or open position.

While the resilient means for retracting the respective parts has been shown interposed between the finger grip lever 9 and the palm gripping means 5, an open coil spring may be placed in a suitable opening in the under face of the lever extension 8 to exert its force against the base member 4 to effect the return of the respective parts to operative position.

The pivotal axis of the articulated blade supporting member 1 is disposed in the longitudinal center of the blade members 6 which obviates the necessity for radially cutting the teeth members and permits easy lapping of the blades to provide complementary cutting edges. Further sharpening of the blade members may be accomplished by grinding or stoning in substantially

the same manner as is done with conventional scissors or shears.

The lateral shearing alignment or frictional contact between the blade members 6 is effected by means of a set screw 14 disposed in the base member 4 adjacent to and to the rear of the longitudinal center of the pivot member 2. The blade member 1 is held in movable relation to the screw 14 by a compression spring 15 mounted on the pivot 2 and retained in the counterbored recess 16. A recessed male threaded bearing member 17 screwed into the base member 4 provides supporting means for the outer end of the pivot 2 and compresses the spring 15 to maintain operative alignment between the blade members 6.

The disposition of the set screw 14 to the rear of the pivot 2 increases the tendency toward maintaining lateral contact between the blade members 6 and to a limited extent provides a self lapping means while the blades are being operated.

Referring to Figure 1, the dotted lines 11a extending downward from the finger lever 9, form an eye or loop through which the fingers pass when gripping the device. Downward pressure of the fingers against said eye member when distending the hand returns the articulated blade member 1 to its operative or open position. In certain instances this may be the preferred form of retractive control for specific uses.

Among the advantages to be obtained from a rigid blade supporting base member in which the articulated blade may be controlled by the palm and fingers is the entire absence of undulating motion experienced when using the conventional shears or scissors. Following a marked course for cutting becomes a comparatively simple matter. The shears may be slid along using the hand to guide the material to be cut, and equal facility is experienced when using the device to trim or cut material that is not suitable for laying out flat when cutting same. These and other advantages will be readily apparent to those skilled in the art.

What is claimed as the invention and desired to be secured by Letters Patent, is:

1. A shearing means comprising, a blade sup-

porting base member having an angular gripping means integral therewith, an articulated blade supporting member pivotally disposed in the base member, a lever member pivotally disposed in the base member and adapted to operatively engage the articulated blade supporting member.

2. A shearing means according to claim 1, and resilient means for retracting the blade and lever members to operative position.

3. A shearing means comprising, a blade supporting base member having a vertically disposed gripping means integral therewith, an articulated blade supporting member pivotally suspended in the base member, a lever member pivotally disposed in the base member and adapted to operatively engage the articulated blade supporting member, resilient means for retracting the blade and lever members to operative position, and an adjusting means mounted in the base member to frictionally engage the articulated blade member for regulating the lateral frictional contact between the respective blade members.

4. A shearing means comprising, a blade supporting base member having a vertically disposed angular gripping means integral therewith, an articulated blade supporting member pivotally disposed in the base member, a lever member pivotally disposed in the base member and adapted to operatively engage the articulated blade member, resilient means mounted on the articulated blade pivot member for holding the said member in operative alignment, resilient means interposed between the lever member and the gripping means for retracting the articulated blade member to operative position, adjusting means mounted in the base member to frictionally engage the articulated blade member for regulating the lateral frictional alignment between the respective blade members.

5. A shearing means according to claim 4, and a removable bearing member mounted in the base member for supporting the outer end of the articulated blade pivot, said bearing being adapted to compress the resilient member mounted on the articulated blade pivot to hold said blade in operative alignment.

FRED B. SEEBERGER.
